UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

GAS-CLEANING APPARATUS.

Application filed May 4, 1925. Serial No. 27,837.

My invention relates to improvements in gas cleaning apparatus, with special reference to means for collecting and removing dust from streams of air or gas.

5 The object of the invention is to provide a highly efficient dust catching or recovering apparatus adapted to be interposed in gas and air stacks, and, which shall be wholly composed of stationary (non-rotative) parts; 10 which shall be of little weight; of low cost; adapted to be made of various metals suited to the varying purposes; and be easy of maintenance and repair.

A special purpose of the invention is to 15 provide a dust catching apparatus which in one of its several forms shall be most admirably adapted for employment at the top of stacks, such as cupolas, where at times high temperatures must be endured, without 20 lessening the efficiency of the apparatus or materially shortening its life.

The invention will be clearly understood upon reference to the drawings that form 25 part of this specification, and in which Fig. 1 is a vertical section of one form of the apparatus embodying my invention; Fig. 2 is a horizontal section thereof on the line 2—2 of Fig. 1; Fig. 3 resembles Fig. 1 but illustrates a modified construction; Fig. 4 illustrates a further modification; Fig. 5 is a vertical section illustrating a multiple arrangement of the gas purifying or dust catching units. Fig. 6 is a side view of the apparatus 30 of Fig. 5 on a reduced scale. Figs. 7 and 8 are plan views illustrating the different arrangement of the dust catching units at the top of the stack. Fig. 9 is a plan view partly 35 in section of a multiple unit apparatus as adapted for employment at the top of a cupola; Fig. 10 is a side elevation thereof, partly in section; and Fig. 11 is a side elevation, on a reduced scale, showing different methods of opening the top of the structure to permit free exit of the gases; also easy 40 entrance to the interior of the structure.

Referring to Figs. 1 and 2, the part 2 represents the shortened upper end of a stack, such as the exhaust stack at the top of a water gas machine; through which not 45 only gases but flames rise at intervals. Any dust catching means placed directly above such a machine would be subjected to the intense radiant heat of the flame, and as a first step and precaution I remove the dust 50 catcher from that position and place it at

one side of the stack where it is hidden or shaded from the radiant heat and will have a longer life.

With reference to the other drawings, it is seen that this is a feature that persists in all 60 of those forms of my apparatus which are placed at the tops of or within or between the top and bottom of the vertical fire stacks. Carrying out the importance of this idea, it is to be noted that by this invention only the 65 tuyère ring or centrifugal element proper is exposed in any manner within the dust catcher casing. All other parts are exposed to the outer atmosphere on the outside of the dust catcher casing. In such positions they 70 are readily accessible and are of long life.

The next special advantage to be noted flows from the fact that the dust catcher casing need be no larger or higher than necessary to contain the centrifugal element 75 or tuyère ring and afford adequate gas passages about that element. In consequence, the size and weight of the casing are most conveniently small.

The part 3 is the centrifugal element or 80 tuyère ring above mentioned. It is composed of a circumferential series of tangentially positioned vertical tuyère blades 3' suitably fastened or held at the top and bottom. These present the many tangential entrance tuyères 4. The before mentioned casing is a bracket like box 5 which receives the top of the stack 2 and extends to one side thereof. The upper and lower ends of the tuyère ring 3 are accommodated in holes in 85 the top 5' and bottom 5" of the casing 5. By preference the top of the tuyère ring is characterized by an overhanging abutment ring 3", and a peripheral extension of that ring serves as a support for the tuyère ring, 90 hanging from the margin of the hole in the casing top 5'. For additional support, the lower ends of the tuyère blades 3' may rest on the floor 5" of the casing. The opening 6 within the ring 3" is the gas outlet. This 95 may open directly to the atmosphere or, if desired, into the base of a stack extension 2'. The whole lower end of the tuyère ring 3 is open. A short distance below it I suspend a bottom disk 7, leaving an annular dust discharge slot 8 between it and the extreme 100 lower end of the tuyère ring 3. Hanging from the casing part 5" and surrounding the lower end of the tuyère ring and the plate 7 is a larger ring 9, and, the dust re- 105 110

ceiving cone or bottom 10 hangs from the ring 9. 11 is the dust discharge pipe. Special note is to be made of the annular expansion cavity or race 8" directly at the 5 lower end of the tuyère ring and at the periphery of the plate 7.

The dust carrying gases which rise in the stack 2 are diverted by the bracket like casing and distributed to the many slit-like 10 tangential tuyères 4. Entering the tuyères with considerable velocity the dust burdened 15 gases take on a rapid whirling motion within the barrel-like tuyère or tuyère ring; with the result that the dust particles are 20 immediately deposited upon the inner surfaces of the tuyère ring and accompany the gases in whirling against those surfaces. The presence of the overhanging abutment 25 3" prevents the escape of the peripherally collected dust at the top of the tuyère ring and very quickly the dust is delivered downward and while still in a whirling condition 30 encounters the annular discharge slot 8. At that point the whirling dust finds instant relief into the expansion space 8". That space and the cone 10 being closed, the gases are not permitted to escape at the bottom of the tuyère and instead whirl toward the center and upward and out through the 35 opening 6 and the stack 2'. Meantime, the accumulating dust drains away through the discharge pipe 11.

Most conveniently, the upper corner of the 35 casing 5 comprises a drop door 12 swung from its upper edge and so arranged that it may also be swung outward and upward to permit access to the interior of the casing. But as a rule, it is only employed to 40 open the stack directly to the outer atmosphere, that is, as a cut out for the dust catcher. Further, there are times when the flame intensity in the stack 2 is so great as to make the use of this cut out desirable to prevent the burning of the tuyère blades.

45 In dealing with very fine dusts of little specific gravity, there is always a tendency for them to be carried away by the moving gases. To obviate this tendency I may add to the top of the tuyère ring a part which 50 serves to intercept and discharge the fine dust. This part, see Figure 3, comprises the top collecting ring or race 13 resting upon the top 14 of the casing. The ring is considerably larger than the interior of the tuyère and the dust particles on reaching the top of the tuyère whirlingly expand in the race. They are discharged therefrom 55 through the tangential nozzle 15. Conveniently, the down pipe 16 of the latter may 60 join the dust discharge pipe below the bottom cone 17 of the dust catcher.

In lieu of the conical bottom above described, I sometimes employ a bottom bowl 65 18, as shown in Fig. 4. This bowl is so much larger than the tuyère ring 19 as to

provide an expansion race 18', so that the elimination of the dust is ensured. The bowl is preferably characterized by a tangential dust outlet nozzle 20, and has a down pipe 21 that leads to a suitable closed pocket. 70

It will at once be obvious that where large stacks are to be served, it is both desirable and advantageous to surround the top of the stack with a plurality of the described dust catching units. Such arrangements are illustrated by the units 23, 24, in Figures 7 and 8.

Similarly, a plurality of dust catching units, with great advantage, may be employed in connection with a large main or 80 horizontal conduit 25, as shown in Figure 6. The details of this structure are better represented by Figure 5, wherein it will be seen that the transversely extensive but vertically low rectangular casing 26 contains a plurality of the described dust collecting units 27.

An especially advantageous adaptation of this invention to the tops of cupolas is represented in Figs. 9 and 10. A cupola stack comprises a thin metal shield 28 and a lining 29 of brick. It is of no great strength and if external supports are to be avoided the dust catching apparatus on top of the stack must be of minimum weight. To this end, I attach and virtually balance upon the top of the stack a light floor structure 30 which supports a correspondingly light top 31 and vertical walls 32. Directly above the cupola stack the top 31 is interrupted to receive the deflecting walls 33, which, it will 100 be noted, may comprise suitable drop doors or, if desired, doors which open upwardly, as shown at 34. The overhanging parts 35 of the casing contain the four dust catching units 36, the construction of which will now 105 be apparent. It remains only to state that the outlet openings 36' aggregate an area which preferably exceeds the cross sectional area of the cupola stack. The tuyère should have an area still greater in the aggregate. 110 The tops of the dust catching unit may be equipped with extension stacks such as 37; likewise they may be equipped with dust catching races after the manner illustrated in Figure 3.

115 This balanced cupola top or casing is held in place by means of tie rods 38 extending from the bottom thereof to the lower part of the stack. Obviously, light brackets between the floor 30 and the stack sides may take the place of the tie rods or cables 38.

120 It is believed that the structure represented in the several figures of the drawings, and in such forms as will readily suggest themselves to those skilled in the art, will at once be accepted as a complete and commercially practical solution of a hitherto 125 unsolved problem of intercepting and collecting the annoying quantities of dust given off by large stacks. It will also be found 130

distinctly advantageous as a dust intercepting means for inclusion in horizontal air and gas mains.

When constructed of heavier parts, as required to resist heavier pressures, the invention is well adapted for employment with heavier fluids.

Having thus described my invention, what I claim as new and desire to secure by Letters Patent is:

1. The improvement herein described comprising a casing presenting a bottom, a top and sides, in combination with a tuyère ring comprising operatively overlapping substantially tangential blades, and opening through the top and bottom of said casing, a disc centrally positioned at the bottom of said ring and dust receiving means below said disc and depending from the bottom of said casing.

2. The improvement herein described comprising a casing presenting a bottom, a top and sides, in combination with a tuyère ring comprising operatively overlapping substantially tangential blades, and opening through the top and bottom of said casing, and dust receiving means depending from the bottom of said casing and of greater diameter than the lower end of said tuyère ring.

3. The improvement herein described comprising a stack in combination with a bracket like casing at the top thereof, a dust collecting centrifugal tuyère rising vertically in the offset portion of said casing, and itself providing the gas exit therefrom.

4. The improvement herein described comprising a stack in combination with a bracket like casing at the top thereof, a dust collecting centrifugal tuyère positioned vertically in the offset portion of said casing and itself providing the gas exit therefrom, and a cut out door in the portion of said casing above the stack.

5. The improvement herein described comprising a stack, in combination with a casing on the top and overhanging the sides thereof, a plurality of dust catching centrifugal tuyère units disposed vertically in the overhanging portions of the casing and each forming a gas exit therefrom, and each said unit being characterized by respective dust receiving elements upon the exterior of said casing.

6. The herein described improvement comprising a barrel like tuyère ring presenting a plurality of longitudinal slit-like tangential tuyères, a disk suspended below the ring, a race surrounding said disk and the lower end of said ring, and means for discharging the heavier substances from said race.

7. The herein described improvement comprising a barrel like tuyère ring presenting a plurality of longitudinal slit-like tangential tuyères, a disk suspended below the ring, a race surrounding said disk and the lower end of said ring, and means for discharging the heavier substances from said race, and a collecting bottom depending from said race.

In testimony whereof I have hereunto set my hand this 30th day of April A. D. 1925.

CHARLES GILBERT HAWLEY.
